ABSTRACT

In an electronic musical instrument, a sustain keyer circuit comprises a field effect transistor, a resistor and a key-operated switch all connected in series between a ground and a power line. An input tone signal supplied to the gate of the FET is keyed to appear at the drain thereof. A capacitor is connected across the key-operated switch. Between the capacitor and the ground is connected another FET which is switched on and off by a rectangular wave having a supra-audible frequency and a variable duty factor thereby exhibiting a variable average resistance, determining a sustain time in cooperation with the capacitor.

KEYER CIRCUIT FOR ELECTRONIC MUSICAL INSTRUMENT

BACKGROUND OF THE INVENTION

1. Field of the invention

The present invention is concerned with a sustain keyer circuit for use in an electronic musical instrument, and more particularly, it relates to an improvement in sustain keyer circuits employing field effect transistors (herein-after referred to simply as FET's), the keyed characteristics of which keyer being represented by its being free of discrepancy in the gate cutoff voltages of the FET's employed.

2. Description of the prior art

Among the sustain keyer circuits using FET's which have been developed of late for use in electronic musical instruments, there is the known arrangement as shown in FIG. 1, which comprises first and second FET's Q₁ and Q₂, which are connected in series to each other from both DC and AC viewpoints. The first FET Q₁ has its source electrode grounded, with the gate electrode being adapted to receive a tone signal through an input terminal T₁, while the drain electrode is connected to the source electrode of the second FET Q₂. This second FET Q₂ is connected, on the one hand, to a voltage source -V_d via a load resistance element R_L, and, on the other hand, to an output terminal T₂ through a capacitor C, thus forming an electronic switch which functions as a keyer. For the sake of keying, a series circuit consisting of a resistance element R_o and a key-operated switch S_o is provided between the voltage source -V_d and the gate of the second FET Q₂, to thereby switch a keying voltage to be applied to the gate electrode of the second FET Q₂, by the operation of the key-operated switch S_o. The above-mentioned series circuit further includes a capacitor C_o connected in parallel therewith, that is, between the gate electrode of the second FET Q₂ and the ground point from AC viewpoint (herein, it is -V_d), thus forming a keying circuit having a time constant determining function, so that the above-mentioned tone signal applied to the FET Q₁ may be derived at the output terminal T₂ upon keying of the key-operated switch S_o. To the gate electrode of said second FET Q₂ is connected a third FET Q₃ at its drain electrode which serves as a sustain time control circuit. The source electrode of the FET Q₃ is grounded and the gate electrode thereof is connected to a slidably movable contact r_a of a variable resistor R_a such as a potentiometer which is interposed between the ground and a variable DC potential source, i.e., the voltage source -V_d.

The above-mentioned sustain keyer circuit and the FET Q₃ constituting a sustain time control circuit are installed in, for example, a console of an electronic musical instrument in number corresponding to a large number, 90-100, of tone generators installed in accordance with the number of the keys of the electronic musical instruments. On the other hand, there is employed only one variable resistor R_a which is assigned to adjust the gate potential of the whole FET's Q₃ to determine the value of resistance between the drain electrode and the source electrode of each of these FET's. By the operation of the variable resistor R_a, the sustain time, namely, the decay time of tone output signals at the whole keyer circuits after the keying-off of the corresponding number of key-operated switches S_o, may be

adjusted simultaneously to the desired period of time by way of the FET's Q₃.

In the aforesaid arrangement, it will be noted that the drain-source resistance of each FET Q₃ will increase as, for example, the position of the slidable contact r_a of the variable resistor R_a is brought closer to the ground side thereof, and that, therefore, the transient time of charging of the capacitor C_o, namely, the sustain time in the electronic musical instrument, will vary in accordance with the potential at the gate of each FET Q₃, in other words, in accordance with the position of the slidabile contact r_a of the resistor R_a.

In detail, the operation of such prior art arrangement will hereunder be explained.

The resistances of resistors R_a and R_o and the DC potential of the power source -V_d are set so that the FET's Q₁ and Q₂ are simultaneously rendered conductive or non-conductive, namely, "on" or "cut-off" in accordance with the opened or closed state of the switch S_o. Along with this, whenever the key-operated switch S_o is closed, the transient characteristic (response) in the course of the beginning of conduction of the FET Q₁ and the FET Q₂ is determined by the time constant which, in turn, is determined by the capacitance of the capacitor C_o and the resistance of the resistor R_o to thereby determine the build-up characteristic of the tone signal derived from the output terminal T₂, while whenever the key-operated switch S_o is opened, the transient characteristic (response) in the course of the ending of conduction of both the FET Q₁ and the FET Q₂ is determined by the time constant which, in turn, is determined by both of the value of capacitance of the capacitor C_o and the value of resistance produced between the drain electrode and the source electrode of the FET Q₃ to thereby obtain the desired decay characteristic of the thus developed tone output signal, which can be termed "sustain time."

In such prior art keyer circuit arrangement, however, there arises inconsistency in the decay times of the tone signals as the output of the keyer circuit following a key-cutoff due to the fact that FET's generally develop various gate cutoff voltages. In addition, the decay amplitude characteristic of the output tone signal does not become exponential and fails to provide a natural sound thereby. This will be well understood by the following explanation with reference to FIGS. 2 a through d. FIG. 2 a shows the gate-source voltage V_{gs} to drain-source current I characteristic of a P channel enhancement mode MOS type FET as the FET Q₂, where V_{th} represents the gate cutoff voltage thereof. Accordingly, when a gate voltage V_g as shown in FIG. 2 b is applied to the gate of the FET Q₂ of the type described above, a rectangular waveform input signal applied to the gate of the FET Q₁ is derived at the output terminal T₂ in the form of a signal having an envelope curve as shown in FIG. 2 c. However, since the gate cutoff voltages of FET's are different from one FET to another by about ± 50 percent, the decay times will be likewise inconsistent as shown by, for example, the broken lines X or Y in FIG. 2 c in accordance with inconsistency in gate cutoff voltages of the FET's which are employed. The foregoing decay characteristic becomes substantially linear in amplitude, and will assume an upwardly curved pattern as shown by the envelope curve in logarithmic scale (dB) in FIG. 2 d. The tone decay having such a decay characteristic in an electronic musical in-

strument is not desirable because of the lack of naturalness in the decaying pattern.

Furthermore, no consideration has been made in the prior art keyer circuit as described above with respect to the problem of signal leakage which develops unavoidably in case of employment of FET's through which tone signals are keyed.

SUMMARY OF THE INVENTION

It is, therefore, a principal object of the present invention to provide a sustain keyer circuits capable of producing a uniform output signal decay characteristic which is free of any inconsistency in the properties of the major components employed.

Another object of the present invention is to provide a sustain keyer circuit for use in an electronic musical instrument, which comprises a keyer FET having its gate electrode adapted to receive an input tone signal and its drain electrode adapted to be keyed by a keyer control voltage and to derive a keyed tone signal thereat, another FET determining the sustain time constant following the opening of a key-operated switch together with a capacitor in a time constant circuit in the sustain keyer and having its gate to vary its equivalent resistance value in accordance with a rectangular waveform signal applied thereto, which signal has a variable duty factor controllable by an instrument player, thereby controlling the sustain characteristic uniformly, independently of the inconsistency in the gate cutoff voltages of the FET's employed.

A further object of the present invention is to provide sustain keyer circuits for use in an electronic musical instrument, which are capable of reducing signal leakage occurring upon mixing a plurality of keyed tone signals.

A still further object of the present invention is to provide sustain keyer circuits for use in electronic musical instruments, which are caused to reduce signal leakage due to the capacitance between the gate electrode and the drain electrode of an FET which is employed as the keyer.

Other objects, features and attendant advantages of the present invention will become apparent from the following description when taken in conjunction with the accompanying drawings.

BRIEF DESCRIPTION OF THE DRAWINGS

FIG. 1 is a circuit diagram illustrating a prior art keyer circuit for use in an electronic musical instrument, said keyer circuit employing FET's therein.

FIG. 2 a through d are charts for explaining the operation of the prior art keyer circuit, wherein FIG. 2 a is a characteristic curve of the gate-source voltage V_{gs} to the drain-source current I in an enhancement mode FET; FIG. 2 b is the waveform of a voltage which is applied to the gate G of FET Q_2 shown in FIG. 1; FIG. 2 c is a waveform showing an output signal at the circuit of FIG. 1; and FIG. 2 d is a waveform showing an output signal at the circuit of FIG. 1 in decibels.

FIG. 3 is a circuit diagram of a sustain keyer circuit illustrating an embodiment of the present invention.

FIG. 4 is a diagram showing a waveform of an output tone signal derived from the sustain keyer circuit of FIG. 3.

FIG. 5 is a circuit diagram representing a modification of a part of the circuit shown in FIG. 3.

FIGS. 6 and 7 are circuit diagrams showing other embodiments of the present invention, respectively.

It should be understood that like parts are indicated by like references and numerals throughout this specification.

DESCRIPTION OF THE PREFERRED EMBODIMENTS

For the sake of simplicity of explanation, the following embodiments of the present invention will be explained by comparing with the prior art circuit which is shown in FIG. 1.

Description will hereunder be made on an embodiment of the present invention with reference to FIGS. 3 and 4.

Referring now to FIG. 3, there is shown a keyer circuit arrangement according to the present invention, which comprises: a p-type enhancement mode FET Q_{11} with grounded source electrodes S , whose gate electrode G is adapted to receive a tone signal through the input terminal T_1 from a known tone generator such as a flip-flop circuit not shown and whose drain electrode D is connected directly to a mixing load resistor R_L as well as to the output terminal T_2 which is common to a plurality of keyer circuits dealing with respectively different tone signals; a series circuit of a key-operated switch S_o , a resistor R_K and a first resistor R_1 connected between the drain electrode of FET Q_{11} and a power source line $-V_d$ to form a keying circuit, a second resistor R_2 connected in parallel with the FET Q_{11} between the drain and source electrodes thereof, a capacitor C_d connected between the juncture of the resistor R_1 and the resistor R_K and the power line (as an A.C. ground), and a p-type enhancement mode FET Q_{22} as a switching element with its drain electrode connected at the connection point between the capacitor C_d and the resistor R_1 and its source electrode grounded. The FET Q_{22} has its gate electrode adapted to receive a rectangular wave signal from a rectangular wave generator A to be rendered alternately conductive and non-conductive.

In operation, when the key-operated switch S_o is opened, the capacitor C_d is charged up by the DC power source $-V_d$ and the drain electrode of the FET Q_{11} is at the ground potential thereby, so that the FET Q_{11} is maintained in its non-conductive state and hence in spite of a tone signal of a rectangular waveform applied to the gate electrode of the FET Q_{11} , no output signal may be derived at the output terminal T_2 , while when the switch S_o is closed, the capacitor C_d will begin to discharge through the resistor R_K and the switch S_o to thereby increase the drain potential of the FET Q_{11} in the negative sense continuously, and as a result, the FET Q_{11} is rendered conductive due to the rectangular waveform signal applied to its gate electrode. Accordingly, with the key operated switch S_o closed, the FET Q_{11} will be rendered non-conductive at a moment the applied input signal has zero level, whereas this FET is rendered conductive at a moment the input signal has a level above a predetermined level V . The resistance between the source-drain electrodes of the FET Q_{11} will become infinitely high under its non-conductive state, while the resistance will become lower under its conductive state which latter resistance is hereinafter designated by R_{o1on} . Furthermore, let us now assume that V_H represents the drain potential of FET Q_{11} in its non-conductive state, and that V_L is the

drain potential of FET Q_{11} in its conductive state, then the signal voltage V_s (peak to peak value of an available A.C. output) which is derived at the drain electrode of the FET Q_{11} can be expressed by the following formula:

$$V_s = V_H - V_L = (V_D - V_K) [R_2/(R_1 + R_2) - R_o/(R_1 + R_o)],$$

wherein:

$$R_o = (R_2 \cdot R_{q1on})/(R_2 + R_{q1on}); \text{ and}$$

V_K represents the voltage across the capacitor C_d .

FIG. 4 shows a graph of the above-mentioned signal voltage at the output terminal T_2 in association with the input signal applied to the input terminal T_1 . As will be apparent from the above-mentioned formula, the output signal voltage is independent of the gate cutoff voltage of the FET Q_{11} .

The build-up characteristic T_r of the output signal upon keying the key-operated switch S_o is determined by a time constant, which is determined by the capacitance of the capacitor C_d and the resistance of the resistor R_K provided that the resistance value of the resistor R_K is set as follows: $R_K \ll$ a parallel resistance composed of " $R_1 + R_2$ " and "the effective resistance of the FET Q_{22} when viewed from its drain side toward the ground side." The resistor R_K is only for determining the build-up time constant, and is not necessarily significant in this invention.

Then, upon release of the key-operated switch S_o , the capacitor C_d begins charging again through the effective (average) resistance of the FET Q_{22} , and the output signal decays gradually thereby. The decaying characteristic of the output signal is determined by a time constant, which is determined by the capacitance of the capacitor C_d and mainly the effective drain-source resistance of the FET Q_{22} (also by the resistance value of the circuit including the resistor R_1 , the resistor R_2 and the FET Q_{11}). Accordingly, the decaying characteristic of the tone signal after keying-off, namely the so-called sustain characteristic, can be varied by varying the effective drain-source resistance of the FET Q_{22} as required.

Referring to FIG. 5, there is shown an example circuit for controlling the FET Q_{22} , in which arrangement is provided so that the output signal produced in a triangular waveform having a predetermined repetition frequency, such as 40 kHz, which is higher than the audible frequency and which is obtained from a triangular waveform generator G is applied via a DC blocking capacitor C' and a diode D in this order, to the input side of the known Schmitt trigger circuit F which is comprised of elements such as transistors and resistors, and that the rectangular waveform output terminal T_o of the Schmitt trigger circuit F is connected to the gate electrode of the FET Q_{22} having other two electrodes connected to the ground and the resistor R_1 , the capacitor C_d , and the resistor R_K —which constitutes the keying circuit—of the sustain keyer circuit so that the rectangular waveform output signal of the aforesaid predetermined repetition frequency which is produced in said Schmitt trigger circuit F is applied to the gate electrode of the FET Q_{22} . By the use of the aforesaid circuit arrangement, the latter is operative in such a way that, by changing the DC potential of the point d of connection between the capacitor C' and the diode D via a variable resistor R_B which is interposed

between the voltage source $-V_d$ and the ground, the duty factor (meaning the ratio of a pulse width to a pulse repetition period of the rectangular waveform signal produced at the output terminal T_o) is varied continuously from 0 to 100 percent so that the conducting-to-nonconducting time ratio of said FET Q_{22} (in other words, the time ratio between the momentary conducting time and the momentary non-conducting time of this FET Q_{22}) is changed from 0 to ∞ . It is to be noted that both the sustain keyer circuit and the aforesaid FET Q_{22} are provided in, for example, the console of an electronic musical instrument each in number corresponding to the multiplicit number of tone generators installed in accordance with the number of the keys of the electronic musical instrument. It should be noted also that such elements as the triangular waveform generator G , the variable resistor R_B and the Schmitt trigger circuit F are provided one each in such a way that the combination of these elements is used in common to said multiplicit number of FET Q_{22} to continuously effect simultaneous change of the conductive time of said multiplicity of FET Q_{22} by changing the duty factor of the rectangular waveform signal generated at one output terminal T_o of said Schmitt trigger circuit F .

Let us now assume that the circuitry is in the state such that the DC level of an output signal from the triangular wave generator G is set at a predetermined value by means of the variable resistor R_B and that the duty factor of the rectangular wave produced at the output of the Schmitt trigger circuit F is set at a predetermined value to have the conducting to nonconducting time ratio of the FET Q_{22} set at a predetermined value of the order of, for example, 0.5. When the key-operated switch S_o is opened in such a state of the circuitry, the drain electrode of the FET Q_{22} and the drain electrode of the FET Q_{11} are at the ground potential. So, this latter FET Q_{11} is held in its "cut-off" state. Accordingly, the tone signal which is always applied to the gate electrode of the FET Q_{11} does not appear at the drain side of the FET Q_{11} .

During the foregoing operation of the circuitry, it will be understood that the capacitor C_d which is connected through resistor R_1 to the drain electrode of the FET Q_{11} is in the state of being charged up with the voltage of the power source $-V_d$ by the repetition of the momentary conducting which is effected between the drain electrode and the source electrode of the FET Q_{22} , with the junction between the capacitor C_d and the FET Q_{22} being at a voltage potential substantially equal to the ground potential zero.

On the other hand, when the key-operated switch S_o is closed, the charge on the capacitor C_d which has been in the state of being charged up in the mode of operation described above is discharged through the resistance element R_K which, in turn, is connected in series with said key-operated switch S_o , and along with this, the potentials of both the drain electrode of the FET Q_{11} and the drain electrode of the FET Q_{22} approach the negative potential of the power source $-V_d$. As a result, the FET Q_{11} will become conductive as the tone signal which is applied to the input of the FET Q_{11} is derived, as the output tone signal having a build-up characteristic in accordance with the characteristic of the keyer circuit, at the output terminal T_2 via the drain electrode of this FET Q_{11} . The tone signal thus derived may be amplified as desired to be converted to an audi-

ble sound wave to be given out from such an appliance as a loud speaker not shown.

Next, when the key-operated switch S_0 is opened again, the capacitor C_d which has been in the state of being discharged in the mode of operation described above begins to be charged up with the voltage of the power source $-V_d$ through the average (effective) resistance between the source and the drain of the FET Q_{22} which is rapidly switched to be momentarily conducting and momentarily non-conducting, and along with this, the drain potential of the FET Q_{11} as well as the drain potential of the FET Q_{22} approach the ground potential. Also, when the potentials of these two electrodes constituting a keying terminal take a value in excess of a predetermined potential for a period of time, the FET Q_{11} will produce no output at its drain electrode in the same manner as that described in connection with the opened state of the key-operated switch S_0 . Thus, it will be understood that the decaying characteristic of the output signal is determined by the time constant which is determined by the combination of the capacity of the capacitor C_d , the average resistance resulting from the conducting to non-conducting time ratio between the drain and the source electrodes of the FET Q_{22} , and a series resistance of resistors R_1 and R_2 (also including the FET Q_{11}).

The aforesaid sustain time or the decay time of an electronic musical instrument may be controlled by varying the DC level of the triangular waveform signal applied to the input side of the Schmitt trigger circuit F, by altering the resistance value of such an element as the variable resistor R_B to thereby alter the duty factor of the rectangular waveform output signal derived at the output of said Schmitt trigger circuit F, whereby continuously varying both the momentary duration of cut-off time and the momentary duration of conducting time of the FET Q_{22} . For example, from a viewpoint of the duty factor, when the momentary conducting period of time is considerably smaller as compared with the momentary cut-off period of time, the length of charge-up time of the capacitor C_d following the opening of the aforesaid key-operated switch S_o (meaning after the key switch-off time) will accordingly become greater. Hence, the sustain time or the decay time of the tone signal which is derived at the output terminal T_2 under the aforesaid condition will be prolonged. Contrariwise, in case where the momentary conducting period of time of the FET Q_{22} is substantially great as compared with its momentary cut-off period of time, the length of charge-up time of the capacitor C_d following the opening of the key-operated switch S_o is reduced, so that the sustain time or the decay time of the aforesaid tone signal will become shorter. In this way, the sustain time of an electronic musical instrument can be controlled. However, in the present invention, the circuitry is arranged in such a way that the gate potential of the FET Q_{22} is controlled at a very high repetition rate, such as 40 kHz so that this FET Q_{22} can alternately become fully conductive and fully non-conductive. As a result, the FET Q_{22} can effect the switching between its cut-off state and its conductive state at a high speed, regardless of the gate cut-off voltage of this FET Q_{22} . Thus, the FET Q_{22} is always held in either the fully conductive or fully non-conductive state, and the average (effective) internal resistance between the drain and the source electrodes of this FET Q_{22} will be caused to vary by the varying duty fac-

tor. Therefore, it is possible to consider that the voltage to current characteristic is of a value equivalent to that of a variable resistor having a linear voltage to current characteristic. Thus, the decay characteristic of the tone signal within the aforesaid sustain time can be obtained as one which is quite close to a complete rectilinear line as shown by the envelope straight lines in logarithmic (dB) scale, so that the optimum auditory exponential decay pattern can be obtained.

10 It is to be noted that, by the employment of only one each of the rectangular waveform signal generating means — such as the triangular wave generator G, the Schmitt trigger circuit F, the diode D and the variable resistor R_B , which are capable of varying the duty factor — it is possible to effect the switching of a number of FET Q_{22} assigned for controlling the sustain time. Thus, the circuitry of the present invention is of many advantages that it can be produced easily and at a low cost, which is highly useful industrially.

20 From the foregoing description of the present invention, it will be understood that a keyed tone signal may be derived at the junction between the resistor R_1 and the keyer FET Q_{11} in each keyer circuit regardless of the inconsistency in the gate cut-off voltages of the FET's which are employed.

25

Practically, in an electronic musical instrument having a large number of keyer circuits, there can arise the case that those keyed signals derived from a plurality of keyer circuits — corresponding in number to the 30 number of half octave tone keys — are mixed, using the resistor R_L in common to the group of keyer circuits. In such an arrangement, there may occur an undesirable signal leakage due to the possibility that the potential of a tone output signal keyed by a keyer circuit 35 being turned on is given to a keyer FET Q_{11} of another keyer circuit. In order to obviate this shortcoming, a class-A buffer amplifier including an FET Q_{33} is provided, as shown in FIG. 6, in each keyer circuit of FIG. 40 3. To the gate electrode of the FET Q_{33} is connected the drain electrode of the FET Q_{11} , and to the drain electrode of the FET Q_{33} is connected the common load resistor R_L as mentioned above. Whereby, the intended tone signal mixing can be performed without a 45 separate damper of signal leakage, since a gate current in FET's is in the order of 10^{-15} ampere in magnitude. A resistor R_S connected to the source electrode of the FET Q_{33} serves to reduce the inter-modulation distortion in the resulting tone signal which may take place 50 due to the changes in the resistance of the FET Q_{11} when looking at from the drain side thereof, which changes are caused by the variations in the drain potential of other keyer circuits.

55 FIG. 7 shows a further embodiment of the present invention which is intended to reduce as much as possible the signal leakage occurring due to the gate-drain capacitance of the keyer FET Q_{11} as a rectangular waveform signal is applied to the input of this keyer FET. The signal leakage is considered to be caused because 60 the applied rectangular waveform contains very high harmonics, in other words, because such rectangular wave contains harmonics over the range up to about 1 MHz clearly.

For the purpose of eliminating the signal leakage, the circuit of FIG. 6 is further provided with another FET 65 Q_{44} between the keyer FET Q_{11} and the input terminal T_1 in each keyer circuit to become of a circuit as shown in FIG. 7. To the gate electrode of the FET Q_{11} is con-

nected the drain electrode of the FET Q_{44} and a capacitor at its one end and grounded at the other end. The input terminal T_1 is connected to the source electrode of the FET Q_{44} whose gate electrode is connected to the power source $-V_D$. The FET Q_{44} which is thus arranged is employed as a resistance element capable of exhibiting a high resistance value, for example, $10 M\Omega$. The capacitor C is set to have the capacitance of $1 pF$, for example. Thus, there is formed a kind of low pass filter which comprises the drain-source resistance of the FET Q_{44} and the capacitance of the capacitor C to thereby eliminate higher harmonics of the rectangular waveform input signal beyond the order of, for example, $16 kHz$, resulting in an extreme reduction of signal leakage due to the gate-drain capacitance of the keyer FET Q_{11} . Furthermore, even if a man's finger contacts the input terminal T_1 , there arises no danger of causing the breakdown of the FET Q_{11} caused by an electrostatic shock, since a high resistance of the FET Q_{44} is interposed between the input terminal T_1 and the FET Q_{11} .

As will be clear from the foregoing description, the novel keyer circuit arrangement of the present invention not only provides desired keyer characteristics by overcoming the problem of inconsistency in the gate cut-off voltages of the FET's employed, but also it can prevent a signal leakage which can take place upon the mixing of keyed tone signals of different keyer circuits and can reduce any signal leakage source line; from the gate-drain capacitance of each keyer FET. It is to be noted that the above-mentioned circuit arrangement is very much suitable for and convenient to circuit integration (IC production).

I claim:

1. In an electronic musical instrument, a sustain keyer circuit comprising:
means establishing a circuit ground;
a power source;
an input terminal for receiving a tone signal to be keyed;
an output terminal for deriving a keyed output;
a first field effect transistor having a source electrode connected to said ground means, a gate electrode connected to said input terminal and a drain electrode connected to said output terminal;
a resistor and a key-operated switch connected in series between said drain electrode and said power source line;
a capacitor connected across said switch;
a switching element having an inherent internal resistance and connected between said capacitor and

said ground means; and
a rectangular wave generator for generating a rectangular wave signal having a frequency above audible range and a duty factor variably controlled by the instrument player, said generator being connected to said switching element for rendering said element alternately conductive and nonconductive in response to said rectangular wave thereby exhibiting an average resistance, which resistance and gate and the capacitance of said capacitor cooperatively determining a decaying time constant of the circuit.

2. The keyer circuit according to claim 1, further comprising:

a second FET having its gate connected to the drain of said first FET and its drain connected to the output terminal and a load resistor for enabling the mixing of keyed tone signals coming from other keyer circuits respectively of the same construction as said keyer circuit, the drains of the respective second FET's being connected to said output terminal and the load resistor.

3. The keyer circuit according to claim 2, in which a third FET is provided between said input terminal and the gate of said first FET for exhibiting a high resistance and a capacitor is connected between the gate and the source of said first transistor, thereby reducing signal leakage of the keyed tone signals due to the gate-drain capacitance of said first FET.

4. The keyer circuit according to claim 1, in which: said switching element is an FET whose drain is connected to said capacitor, and whose gate is connected to said rectangular wave generator.

5. The keyer circuit according to claim 4, in which: said rectangular wave generator comprises a triangular wave generating circuit, a Schmitt trigger circuit adapted to receive the output signals of a repetition frequency coming from said triangular wave generating circuit and also to generate a rectangular wave, and means for varying a DC input potential applied to said Schmitt trigger circuit.

6. The keyer circuit according to claim 5, in which: said means for varying the DC input potential comprises a variable resistor connected to said Schmitt trigger circuit for varying the DC input potential of the Schmitt trigger circuit.

7. A keyer circuit according to claim 1, in which a further resistor is provided between the drain electrode and the source electrode of said first field effect transistor.
